[57] **CLAIM**

The ornamental design for a combined locking bracket and pin for a ladder, as shown and described.

DESCRIPTION

FIG. 1 is a perspective view showing the top, right and front sides of a combined locking bracket and pin for a ladder embodying my new design, the dotted line depiction of a truck and rack being for illustrative purposes only and forming no part of the claimed design; FIG. 2 is an enlarged rear elevational view thereof; FIG. 3 is a left side elevational view thereof; FIG. 4 is a front elevational view thereof; FIG. 5 is a right side elevational view thereof; FIG. 6 is a top plan view thereof; FIG. 7 is a bottom plan view thereof; and, FIG. 8 is a reduced perspective view of the locking bracket and pin for a ladder, the dotted line depiction showing the placement of the pin in the bracket.
